UNITED STATES PATENT OFFICE

ERNST BECKER, OF BERLIN-CHARLOTTENBURG, GERMANY, ASSIGNOR TO SIEMENS & HALSKE, AKTIENGESELLSCHAFT, OF SIEMENSSTADT NEAR BERLIN, GERMANY, A CORPORATION OF GERMANY

AIR-COOLED CYLINDER

Application filed November 19, 1930, Serial No. 496,685, and in Germany November 19, 1929.

My invention relates to improvements in air-cooled cylinders and more particularly to air-cooled cylinders for internal combustion engines.

5 In the air-cooled cylinders hitherto known, particularly for internal combustion engines the cylinder liner consists of steel, the combustion chamber with its top cover and gas ducts of light-metal alloy. There exist also 10 cylinders in which the top of the cylinder consists also of steel and in which the valve seats are directly placed in the steel top of the cylinder. The latter design has the disadvantage that the exhaust valve seats last 15 only for a comparatively short time as a result of the poor heat-conductivity of the steel. The flat cylinder top has, however, the advantage that the four valves, in order to obtain a greater cylinder output, can be 20 arranged with parallel stems, without having therefore to incline the valve spindles to one another, as such is the case with light-metal heads in consideration of the shrunk-in valve seats, which cause an unnecessarily 25 great air resistance.

The invention makes it possible to arrange the four valves with parallel stems and therefore with the smallest air resistance, this advantage not being affected by the 30 poor heat conductivity of the cylinder top of steel. According to the invention the top of the cylinder is made of a beryllium bronze alloy of great strength and good heat-conductivity. This top contains at the 35 same time the valve seats, whilst the gas ducts are arranged in the light-metal head, resting on the beryllium top.

The accompanying drawing illustrates an embodiment of the invention. 1 denotes the 40 steel liner of the cylinder, 2 the cylinder top of beryllium bronze, which according to the invention is designed in the form of a pot and which is provided with ribs and thread at the inside and which is screwed on in a 45 heated state; this top contains at the same time the valve seats 3. 4 represents the cylinder head which in this arrangement is relieved of the thermal and mechanical stresses inherent in the previous constructions and which substantially only serves

to guide the gases. At 5 are shown the cooling ribs of the steel liner 1, and which may be arranged in any suitable manner well known in the art. In the present example they are cut into the solid wall of the steel 55 liner 1.

The advantages of the cylinder consist in the possibility of arranging four valves on a flat cylinder top, whereby it is possible to obtain an unusually good cooling of the 60 valves as a result of the excellent heat-conducting qualities of the employed material.

The described combination of the cylinder top of beryllium bronze with the light-metal head has further the advantage, as compared with a cylinder top and cylinder head of one piece of beryllium bronze, of a considerable saving in weight and a considerable reduction in cost. 65

I claim as my invention:

1. An air cooled cylinder particularly for internal combustion engines, having a ribbed steel cylinder portion, a cylinder top of a beryllium alloy of high tensile strength and good heat conductivity, shrunk onto 75 one end of said steel cylinder, and a light-metal cylinder head attached to said top, said top containing the engine valve seats and said head containing the gas ducts leading to and from said seats. 80

2. An air cooled cylinder particularly for internal combustion engines, having a ribbed steel cylinder portion, a pot shaped cylinder top of a beryllium alloy of high tensile strength, threaded and shrunk onto one 85 end of said steel cylinder, and a light-metal cylinder head attached to said top, said top containing the engine valve seats and said head containing the gas ducts leading to and from said seats. 90

In testimony whereof I affix my signature.

ERNST BECKER.
